UNITED STATES PATENT OFFICE.

JULIUS FOX, OF CLEVELAND, OHIO.

AEROPLANE.

1,338,128.

Specification of Letters Patent. Patented Apr. 27, 1920.

Application filed July 21, 1919. Serial No. 312,143.

To all whom it may concern:

Be it known that I, JULIUS FOX, a citizen of Hungary, (having declared my intention to become a citizen of the United States,) residing at Cleveland, in the county of Cuyahoga and State of Ohio, have invented certain new and useful Improvements in Aeroplanes, of which the following is a specification.

10 The usual provision in a biplane of the planes positioned with one directly beneath the other prevents the upper plane from offering resistance to the air upon the dropping of the aeroplane while the air 15 acting upon the lower plane upsets the craft and my invention renders the craft more stable and less liable to upset by positioning one of the planes slightly rearwardly of the other.

20 I also provide convex ailerons for receiving the air waves leaving the smooth lower part of the fuselage and passing upwardly in circular movement. The aeroplane is further rendered more safe by 25 means of a gas or vacuum chamber, the entire construction of the device being simple and the craft being easily steered but controlled by the pilot.

With these general objects in view the 30 invention consists of the novel combination and arrangement of parts hereinafter more fully described in connection with the accompanying drawings and then claimed.

In the drawings like reference characters 35 designate corresponding parts throughout the several views, and

Figure 1 is a side elevation of the invention,

Fig. 2 is a front view thereof,

40 Fig. 3 is a top plan view of the same,

Fig. 4 is an enlarged detail sectional view of a portion of the lower plane taken upon line IV-IV of Fig. 2,

45 Figs. 5 and 6 are enlarged sectional views taken upon lines V-V and VI-VI respectively of Fig. 3,

Fig. 7 is a transverse sectional view taken upon line VII-VII of Fig. 1,

Fig. 8 is a rear elevation of empennage,

50 Fig. 9 is a vertical sectional view taken upon line IX-IX of Fig. 8, and

Fig. 10 is a view partly in section through the vertical rudder taken upon line X-X of Fig. 1.

55 My aeroplane provides a fuselage 10 having a casing 11 longitudinally of the

bottom thereof adapted for normal inflation with gas for adding buoyancy to the craft, although air may fill the casing 11 if desired or a vacuum may be formed by 60 any convenient means, a propeller 12 upon the nose 13 of the fuselage serving to draw the craft forwardly while the pilot is positioned in a cabin 14 in the top portion of the fuselage.

65 A chassis 15 beneath the fuselage has ground wheels 16 while a double vertical rudder 17 is employed for steering the craft by means of suitable pull cords 18. An empennage surrounds the rudder 17 comprising an arcuate plate 19 having a bracket 20 to which the rudder is pivoted while a substantially U-shaped frame 21 carried by the ends of the plate 19 has three rearwardly projecting aerofoils 22 projecting 70 therefrom, said aerofoils being dished or convexed with their open end sides adapted for catching the upward currents of air.

75 Two main aerofoils 23 and 24 are transversely carried by the fuselage 10 to the upper aerofoil 24 being rearwardly of the lower aerofoil 23 whereby the lower surfaces of both aerofoils will be engaged by the air upon the dropping of the aeroplane. Both of the aerofoils 23 and 24 are formed 80 of a plurality of concaved sections 25 for receiving the air in their open lower sides as best illustrated by the sectional view of portions of the upper and lower aerofoils shown in Figs. 5 and 6 respectively. 90

A forwardly projecting concaved aerofoil 26 is positioned beneath the forward portion of the fuselage while similar forwardly projecting aerofoils 27 are provided upon the lower plane 23 at opposite 95 sides of the fuselage.

Opposite fins 28 longitudinally of the fuselage 10 are formed in concaved sections 29 for catching upward currents of air. Suitable supports 30 and braces 31 are provided between the main aerofoils or wings 23 and 24. The entire structure is compact and complete and the pilot within the cabin 14 having control of the motor for the propeller 12 in the usual manner readily steers 100 the aeroplane by the rudder 17. Should the motor become stalled and the aeroplane begin to drop downwardly, the resistance of the concaved aerofoils 22, 23, 24, 26, 27 and 28 offers great resistance and assists to support the aeroplane in the air for slow descent after the manner of a parachute. 110

The casing 11 is also serviceable for holding shiftable ballast for maintaining the craft upon an even keel when the propeller 12 is at rest and the craft is dropping downwardly, the upper wing or plane 24 serving to catch the air as well as the lower plane 23 and the fins 28. A safe air craft is provided and while the form of the invention herein set forth is believed preferable it may nevertheless be understood that minor changes may be made herein without departing from the spirit and scope of my invention.

What I claim as new is:—

- 15 1. An air craft comprising a fuselage, lower main aerofoils carried thereby, upper main aerofoils carried by the fuselage rearwardly of the lower main aerofoils, said aerofoils each being formed of a plurality 50 of downwardly opening dished sections positioned side by side transversely of the fuselage, opposite fins longitudinally carried by the fuselage rearwardly of said aerofoils and composed of a plurality of downwardly opening concaved sections positioned 55 side by side longitudinally of the fuselage, forwardly projecting aerofoils beneath the fuselage and upon the lower main aerofoils at opposite sides of the fuselage, and a rudder at the stern of the fuselage.
- 20 2. An aeroplane comprising a fuselage having a forwardly positioned propeller, an empennage formed of a substantially semi-circular plate attached to the stern of the 60 fuselage, a frame rearwardly projecting from the ends of the plate at the opposite sides of the craft, rearwardly projecting aerofoils carried by the frame having dished 65 lower surfaces, and a vertical double rudder pivoted centrally to said plate within the frame.
- 25 3. An aeroplane comprising a fuselage having a forwardly positioned propeller, an empennage formed of a substantially semi-circular plate attached to the stern of the 70 fuselage, a frame rearwardly projecting from the ends of the plate at the opposite sides of the craft, rearwardly projecting aerofoils carried by the frame having dished lower surfaces, a vertical double rudder pivoted centrally to said plate within the frame, main sustaining planes carried by the fuselage positioned one behind the other and having dished lower surfaces, and fins mounted longitudinally upon the fuselage 75 between said main planes and the empennage and having dished lower surfaces.
- 30 4. An aeroplane comprising a fuselage having a forwardly positioned propeller, an empennage formed of a substantially semi-circular plate attached to the stern of the fuselage, a frame rearwardly projecting from the ends of the plate at the opposite sides of the craft, rearwardly projecting aerofoils carried by the frame having dished lower surfaces, a vertical double rudder pivoted centrally to said plate within the frame, main sustaining planes carried by the fuselage positioned one behind the other and having dished lower surfaces, fins mounted longitudinally upon the fuselage 80 between said main planes and the empennage and having dished lower surfaces, a cabin forwardly of the fuselage, steering cords for said rudder, forwardly projecting aerofoils beneath the fuselage and upon the lower main plane at opposite sides of the fuselage, and an inflatable buoying member longitudinally beneath the fuselage.

In testimony whereof I affix my signature. 80

JULIUS FOX.
